F. KRAEMER.
ELECTRIC SWITCH.
APPLICATION FILED MAR. 25, 1916.

1,208,576.

Patented Dec. 12, 1916.

UNITED STATES PATENT OFFICE.

FRANK KRAEMER, OF MILWAUKEE, WISCONSIN, ASSIGNOR, BY DIRECT AND MESNE ASSIGNMENTS, TO PAN-AMERICAN TOOL COMPANY, OF MILWAUKEE, WISCONSIN, A CORPORATION OF WISCONSIN.

ELECTRIC SWITCH.

1,208,576.

Specification of Letters Patent. Patented Dec. 12, 1916.

Application filed March 25, 1916. Serial No. 86,547.

To all whom it may concern:

Be it known that I, FRANK KRAEMER, a citizen of the United States, residing at Milwaukee, in the county of Milwaukee and 5 State of Wisconsin, have invented certain new and useful Improvements in Electric Switches, of which the following is a specification.

This invention relates to electric switches 10 and has for its object the provision of a switch adapted to make and break a circuit with sufficient rapidity to insure against sparking and consequent burning of the contacts.

15 A further object of my invention is the provision of a device of compact and simple construction whereby the circuit will be rapidly closed when the switch is manually actuated and automatically and rapidly 20 broken when the switch is released.

25 A further object of my invention is the provision of a manually operable switch to make and break a plurality of circuits, the rapidity of the circuit-making and breaking 30 operation being independent of the will of the operator and of means connected to one of the circuit-controlling means of the switch to vary the quantity of the current flowing therethrough.

35 Further objects and advantages of my invention will be apparent as it is better understood by reference to the following specification when read in connection with the accompanying drawing, illustrating a preferred embodiment thereof, in which—

Figure 1 is a side elevation of the switch according to my invention; Fig. 2 is an end elevation of the circuit-closing means; Fig. 3 is a side elevation, partially in section, of 40 a portion of the structure illustrated in Fig. 1 showing a different position of the contact members, and Fig. 4 is a diagrammatic view illustrating one application of the switch.

Referring to the drawing 1 indicates a 45 suitable base, preferably of metal, provided with arms 2 to which the grip 3 is secured. Mounted on the base 1 is a support 4 of insulating material for the resistance coils 5 and 6, the purpose of which will be here- 50 after more fully explained.

Slidably mounted in a suitable bearing 7 in the base 1 is a plunger 8 having an operating handle 9' which may be grasped by the fingers of the operator and drawn toward the grip 3 to actuate the mechanism. 55 A pin 9, disposed through the bearing 7 and engaging a slot 10 in the plunger 8 limits the longitudinal movement and prevents rotation thereof. The plunger 8 is biased to the position indicated in Fig. 1 by a 60 spring 11 disposed between the bearing 7 and a shoulder 12 on an insulating member 13 secured to the plunger 8.

A plate 14 of conducting material is secured to the end of the insulating member 65 13 and is provided with contact members 15 and 16 extending laterally therefrom. Secured to the insulating support 4 on either side of the insulating member 13 are metallic supports 17 and 18 upon which the 70 contact arms 19 and 20 are pivotally mounted. Adjustable screws 21 in the path of the ends 22 of the arms 19 and 20 limit the movement of the arms in the direction in which they are biased by springs 23 secured 75 to the supports 17 and 18. Pivotally mounted on the arms 19 and 20 are auxiliary contact arms 24 and 25 biased in the direction of the contact arms 19 and 20 by springs 26 and retained in properly spaced relation 80 with the contact arms 19 and 20 by shoulders 27 formed thereon. Plates 28 and 29 of insulating material are secured to the auxiliary contact arms 24 and 25. A fixed contact member 30 is secured to the insulating support 4 in the path of the contact arm 20.

The operation of the above-described mechanism will be readily apparent from the following brief description: When the 90 operator desires to close the circuits he draws the handle 9' toward the grip 3, thus carrying the plunger 8 and the contact members 15 and 16 toward the auxiliary contact arms 24 and 25, incidentally compressing the 95 spring 11. The plates 28 and 29 of insulating material are so disposed as to be in the path of the contact members 15 and 16 and hence the circuit is not immediately closed. Continued movement of the contact 100

members 15 and 16, however, depresses the auxiliary contact arms 24 and 25 and also the contact arms 19 and 20 and when a predetermined position has been reached the contact members 15 and 16 will ride off of the insulating plates 28 and 29 and will engage the contact arms 19 and 20 to close the circuit with sufficient rapidity to prevent sparking. Upon further movement of the plunger 8 the contact arm 20 will engage the fixed contact member 30. When the operator desires to break the circuit the handle 9 is released and the spring 11 returns the parts to normal position. The contact members 15 and 16 remain in engagement with the contact arms 19 and 20 and the auxiliary contact arms 24 and 25 until a predetermined position is reached. At this position the contact arms 19 and 20 are stopped by the adjustable screws 21 and the auxiliary contact arms 24 and 25 are thereafter moved against the tension of the springs 26 until the contact members 15 and 16 ride past the ends of the auxiliary contact arms 24 and 25 whereupon the circuit is quickly broken.

I have illustrated in Fig. 4 an application of my switch in circuits employed in controlling an electric tool (not shown). In order that the switch may be readily connected to the circuits I provide binding posts 31, 32, 33 and 34. The binding post 31 is connected by a suitable conductor 35 to the plate 14, carrying the contact members 15 and 16 and by a conductor 36 to a lead 37 from a source of current. The contact arm 20 is connected by a suitable conductor 38 to the resistance coil 5 which is in turn connected in series with the resistance coil 6. A conductor 39 connects the fixed contact member 30 to the resistance coils 5 and 6 intermediate thereof. A conductor 40 connects the free end of the resistance coil 6 to the binding post 34 and from the binding post 34 a conductor 41 leads to a motor 42 which is employed in operating the automatic circuit maker and breaker (not shown) and controls the speed of operation of the tool. A conductor 42 connects the motor 42 to the binding post 33 which is connected by a conductor 43 to a lead 44 from the source of current. It will be apparent, therefore, that when the contact member 16 engages the contact arm 20 a circuit including the motor will be closed through the resistance coils 5 and 6 and that when the contact arm 20 engages the fixed contact member 30 the resistance coil 5 will be cut out allowing a larger quantity of current to flow to the motor with a consequent increase of speed thereof. The binding post 32 is connected by a suitable conductor 45 to the contact arm 19 and by a conductor 46 to the solenoid coil 47 forming a part of the electric tool. The free end

of the solenoid coil 47 is connected by a conductor 48 to the conductor 42 leading to the binding post 33. Consequently when the contact member 15 engages the contact arm 19 a circuit is closed through the solenoid coil 47.

It will be apparent from the foregoing that I have perfected a switch for rapidly making and breaking a plurality of circuits and for varying the quantity of current flowing through one of the circuits. Obviously my invention may be employed to close a single circuit with or without the resistance coils.

I am aware that various changes in the form and proportion of parts and in the details of construction of my invention may be made without departing from the spirit or sacrificing the advantages thereof and I, therefore, reserve the right to make all such changes as fairly fall within the scope of the invention as indicated in the following claims.

I claim:

1. In an electric switch, the combination of a reciprocable contact member biased in one direction, a pivoted contact arm extending into the path of and biased in the direction of said contact member, an auxiliary contact arm in the path of said contact member pivotally connected to and biased toward said first-mentioned contact arm, insulating means on one face of said auxiliary contact arm, and means for actuating said contact member.

2. In an electric switch, the combination of a reciprocable contact member biased in one direction, a pivoted contact arm extending into the path of and biased in the direction of said contact member, an auxiliary contact arm in the path of said contact member pivotally connected to and biased toward said first-mentioned contact arm, insulating means on one face of said auxiliary contact arm, means for actuating said contact member, and a fixed contact member in the path of said contact arm.

3. In an electric switch, the combination of a reciprocable contact member biased in one direction, a pivoted contact arm extending into the path of and biased in the direction of said contact member, an auxiliary contact arm in the path of said contact member pivotally connected to and biased toward said first-mentioned contact arm, insulating means on one face of said auxiliary contact arm, means for actuating said contact member, a fixed contact member in the path of said contact arm, and means connected to said contact arm and fixed contact member to regulate the flow of current through the switch.

4. In an electric switch, the combination of a reciprocable plunger, a contact member

secured thereto, a spring to normally retain said plunger in a predetermined position, manually operable means to move said plunger against said spring, a pivoted contact 5 arm extending into the path of and biased in the direction of said contact member, an auxiliary contact arm in the path of said contact member pivotally connected to and biased in the direction of said first-mentioned contact arm, and an insulating member on the face of said auxiliary contact arm adapted to be first engaged by said contact member as it is moved by said manually operable means.

15 5. In an electric switch, the combination
of a reciprocable plunger, a contact mem-
ber secured thereto, a spring to normally
retain said plunger in a predetermined po-
sition, manually operable means to move
20 said plunger against said spring, a pivoted
contact arm extending into the path of and
biased in the direction of said contact mem-
ber, an auxiliary contact arm in the path of
said contact member pivotally connected to
25 and biased in the direction of said first-men-
tioned contact arm, an insulating member
on the face of said auxiliary contact arm
adapted to be first engaged by said contact
member as it is moved by said manually
30 operable means, and a fixed contact member
in the path of said contact arm.

6. In an electric switch, the combination of a reciprocable plunger, a contact member secured thereto, a spring to normally retain said plunger in a predetermined position, manually operable means to move said plunger against said spring, a pivoted contact arm extending into the path of and biased in the direction of said contact member, an auxiliary contact arm in the path of said contact member pivotally connected to and biased in the direction of said first-mentioned contact arm, an insulating member on the face of said auxiliary contact arm adapted to be first engaged by said contact member as it is moved by said manually operable means, a fixed contact member in the path of said contact arm, and resistance elements connected to said contact arm and fixed contact member.

7. In an electric switch, the combination of a reciprocable plunger, a contact member secured thereto, a spring to normally retain said plunger in a predetermined position, manually operable means to move said plunger against said spring, a pivoted contact arm extending into the path of said contact member, a spring engaging said contact arm to move it toward said contact member, a stop to limit the movement of said contact arm, an auxiliary contact arm pivotally mounted on said first-mentioned contact arm in the path of said contact member, a spring to resiliently maintain

said contact and auxiliary contact arms in 65
predetermined relative positions, and an in-
sulating member on the face of said auxil-
iary contact arm adapted to be first engaged
by said contact member as it is moved by
said manually operable means. 70

8. In an electric switch, the combination of a reciprocable plunger, a contact member secured thereto, a spring to normally retain said plunger in a predetermined position, manually operable means to move 75 said plunger against said spring, a pivoted contact arm extending into the path of said contact member, a spring engaging said contact arm to move it toward said contact member, a stop to limit the movement of 80 said contact arm, an auxiliary contact arm pivotally mounted on said first-mentioned contact arm in the path of said contact member, a spring to resiliently maintain said contact and auxiliary contact arms in pre- 85 determined relative positions, an insulating member on the face of said auxiliary contact arm adapted to be first engaged by said contact member as it is moved by said manually operable means, and a fixed contact 90 member in the path of said contact arm.

member in the path of said contact member. 9. In an electric switch, the combination of a reciprocable plunger, a contact member secured thereto, a spring to normally retain said plunger in a predetermined position, manually operable means to move said plunger against said spring, a pivoted contact arm extending into the path of said contact member, a spring engaging said contact arm to move it toward said contact member, a stop to limit the movement of said contact arm, an auxiliary contact arm pivotally mounted on said first-mentioned contact arm in the path of said contact member, a spring to resiliently maintain said contact and auxiliary contact arms in predetermined relative positions, an insulating member on the face of said auxiliary contact arm adapted to be first engaged by said contact member as it is moved by said manually operable means, a fixed contact member in the path of said contact arm, and resistance elements connected to said contact arm and fixed contact member. 100 105 110 115

10. In an electric switch, the combination 115
of a reciprocable plunger, contact members
secured thereto, a spring to normally retain
said plunger in a predetermined position,
manually operable means to move said plun- 120
ger against said spring, pivoted contact
arms extending into the path of said con-
tact members, springs engaging said con-
tact arms to move them toward said contact
members, stops to limit the movement of 125
said contact arms, auxiliary contact arms
pivotally mounted on said first-mentioned
contact arms in the path of said contact
members, springs to resiliently maintain

said contact and auxiliary contact arms in predetermined relative positions, insulating members on the faces of said auxiliary contact arms adapted to be first engaged by said contact members as they are moved by said manually operable means, a fixed contact member in the path of one of said con-

tact arms, and resistance elements connected to said fixed contact member and its coöperating contact arm.

FRANK KRAEMER.
